UNITED STATES PATENT OFFICE.

ANDREW S. HALLIDIE, OF SAN FRANCISCO, CALIFORNIA.

BATTERY-SCREEN.

SPECIFICATION forming part of Letters Patent No. 284,735, dated September 11, 1883.

Application filed January 2, 1883. (No model.)

To all whom it may concern:

Be it known that I, ANDREW S. HALLIDIE, of the city and county of San Francisco, State of California, have invented an Improvement 5 in Battery-Screens; and I hereby declare the following to be a full, clear, and exact description thereof.

My invention relates to certain improvements in screens—such as are employed in ore-crushing mills—to allow the pulp to pass 10 through only after it has attained a certain degree of fineness.

My invention consists in certain details of construction and combination of devices, as 15 hereinafter fully described and claimed.

Referring to the accompanying drawings for a more complete explanation of my invention, Figure 1 is a view of my improved screen in a stamp-battery mortar. Fig. 2 is a horizontal section of the screen, showing supporting rods. Fig. 3 is a view of a part of the screen-frame, showing the corrugated groove.

In the construction of my improved screen I employ woven wire, punched metal, or any 25 other suitable screen material, and bend or corrugate the material into angular faces or

flutings *a a*, as shown. Supporting rods or bars *b b* are fixed in the screen-frame, so as to pass down in the angles of the corrugations and give any desired degree of stiffness. In 30 order to retain these screens in position, they are fixed in frames *c*, which are shaped to fit the openings in the mortar in which the screens are to be placed. The top and bottom rails of these frames have corrugated slots or grooves 35 *d* formed in them, corresponding with the shape of the corrugations of the screens, so as to hold them firmly in place.

Having thus described my invention, what I claim as new, and desire to secure by Letters 40 Patent, is—

The herein-described screen, formed with the angular or fluted faces *a a*, in combination with the frames *c*, the rods *b*, fitting into the angles of the screen on opposite sides, and the 45 mortar, as set forth.

In witness whereof I hereunto set my hand.

ANDREW S. HALLIDIE.
